CARBAMOYLPHOSPHONATES

CROSS REFERENCE TO RELATED APPLICATIONS

This application is a continuation-in-part of my co-pending application Ser. No. 85,221, filed Oct. 29, 1970, which is a continuation-in-part of my application Ser. No. 803,962, filed Mar. 3, 1969, now abandoned, which was in turn a continuation-in-part of my earlier application Ser. No. 731,732, filed May 24, 1968, now U.S. Pat. No. 3,627,507.

BACKGROUND OF THE INVENTION

This invention relates to the discovery that a selected group of novel carbamoylphosphonates can be used to regulate the growth rate of plants. More particularly, the compounds of this invention are useful for controlling the growth of woody vegetation.

Related compounds such as the dialkyl carbamoyl-phosphonates are disclosed in U.S. Pat. No. 3,005,010 as herbicides.

SUMMARY OF THE INVENTION

In summary, this invention relates to a novel group of carbamoylphosphonates, the method of using the carbamoylphosphonates to regulate the growth rate of plants and formulations containing carbamoylphosphonates which are useful to regulate the growth rate of plants.

More particularly, the carbamoylphosphonates of 30 this invention are represented by the formula:

wherein:

R₁ is alkyl of one through six carbon atoms, chloroalkyl of one through six carbon atoms containing up to three chlorine atoms, bromoalkyl of one through six carbon atoms containing up to three bromine atoms, alkoxy alkyl of three through seven carbon atoms, alkenyl of two through six carbon atoms, alkynyl of three through four carbon atoms, phenyl or benzyl;

R₂ is hydrogen or methyl;

R_3 is hydrogen, methyl, amino, methylamino, or di-methylamino;

R_2 and R_3 can be taken together to form a ring selected from $-(CH_2)_2-O-(CH_2)_2-$ or $-(CH_2)_n-$ where n is 2-6;

M is selected from the group consisting of ammonium, hydrogen, sodium, lithium, potassium, calcium, magnesium, zinc, manganese, barium or

where R_6 , R_7 and R_8 can be the same or different and each can be hydrogen, alkyl of one through four carbon atoms, or hydroxy alkyl of two through four

1

carbon atoms; and R₉ is hydrogen, alkyl of one through 12 carbon atoms, allyl, benzyl, amino, methylamino, or dimethylamino; R₆ and R₇ can be taken together to form a ring that is $-(\text{CH}_2)_2$ $-\text{O}-(\text{CH}_2)_2$ or $-(\text{CH}_2)_n-$ where n is 2-6 and R₈ and R₉ are H.

Preferred compounds of this invention include those compounds of formula (1) where R_1 is alkyl of one through four carbons or alkenyl of three through four carbons; R_2 and R_3 are each hydrogen; and M is ammonium, hydrogen, or alkali metal such as sodium, lithium or potassium.

The most preferred compounds of this invention are ammonium allyl carbamoylphosphonate, ammonium ethyl carbamoylphosphonate, and ammonium isopropyl carbamoylphosphonate.

Another aspect of this invention relates to the method for modifying the growth rate of plants which comprises applying an effective amount of a compound of formula (1) to a plant to effect modification of the growth rate of said plant. Specifically, the method of this invention results in retarding the growth rate of the treated plants.

Another aspect of this invention relates to formulations of compounds of formula (1) with suitable agricultural adjuvants and modifiers or with tree wound dressings.

DESCRIPTION OF THE INVENTION

30 This invention is founded on the discovery that the
compounds of formula (1) are useful for modifying the
growth rate of plants. In this regard, it has been noted
that the compounds of this invention, as represented by
35 formula (1), are particularly useful to retard the growth
rate of plants without killing them. The compounds of
this invention are particularly useful to retard the
growth of woody plants. The compounds of this invention
can, therefore, be applied in areas such as power
40 line rights-of-way where low-growing and slow growing
vegetation is especially desirable.

In addition to their value as plant growth retardants the compounds of this invention can also be used to control flowering, fruit set and coloration on apples and other fruits. They are useful to control the growth and flowering of ornamental species such as chrysanthemum and azalea.

The compounds of this invention can also be used to prolong the dormancy of perennial plants, and thereby protect the unsprouted buds from frost damage. This can be especially important in the protection of flower buds, which in some years, may sprout early and be killed by cold temperatures.

PREPARATION

The ammonium carbamoylphosphonate salts of this invention are readily prepared by the interaction of the diesters of carboalkoxyphosphonic acids with aqueous 60 solutions of ammonia, primary amines or secondary amines.

This reaction can be considered to occur in two steps as is illustrated by the following equations.

In equations (2) and (3) R is alkyl of one through six carbon atoms, chloroalkyl of one through six carbon

pounds of this invention where R_1 is alkenyl. This reaction is illustrated by equation (4).

atoms containing up to three chlorine atoms, bromoalkyl of one through six carbon atoms containing up to three bromine atoms, alkoxy alkyl of from three through seven carbon atoms, alkenyl of two through six carbon atoms, alkynyl of three through four carbon atoms, phenyl or benzyl; R_{10} is alkyl of one through four carbon atoms, preferably methyl or ethyl; R_1 is alkyl of one through six carbon atoms, chloroalkyl of one through six carbon atoms containing up to three chlorine atoms, bromoalkyl of one through six carbon atoms containing up to three bromine atoms, alkoxy alkyl of three through seven carbon atoms, alkenyl of two through six carbon atoms, alkynyl of three through four carbon atoms, phenyl or benzyl; R_2 is hydrogen or methyl; R_3 is hydrogen, methyl, amino, methylamino, or dimethylamino; R_2 and R_3 can be taken together to form a ring selected from $-(\text{CH}_2)_2-\text{O}-(\text{CH}_2)_2-$ or $-(\text{CH}_2)_n-$ where n is 2-6; M is selected from the group consisting of ammonium, hydrogen, sodium, lithium, potassium, calcium, magnesium, zinc, manganese, barium or

where R_6 , R_7 and R_8 can be the same or different and each can be hydrogen, alkyl of one through four carbon atoms, or hydroxy alkyl of two through four carbon atoms; and R_9 is hydrogen, alkyl of one through 12 carbon atoms, allyl, benzyl, amino, methylamino, or dimethylamino; R_6 and R_7 can be taken together to form a ring that is $-(\text{CH}_2)_2-\text{O}-(\text{CH}_2)_2-$ or $-(\text{CH}_2)_n-$ where n is 2-6 and R_8 and R_9 are H.

The synthesis method, exemplified by equations (2) and (3) involves concurrent or consecutive aminolysis and hydrolysis of the starting dialkyl carboalkoxyphosphonate by interaction with water and the amine reactant.

While equations (2) and (3) represent the route predominantly taken by the reaction when combined in one operation, some hydrolysis may occur during or before aminolysis. However, the postulated reaction sequence as represented by equations (2) and (3) favoring formation of the carbamoyl-phosphonate intermediate is proved experimentally, as it is possible in some instances to isolate the carbamoylphosphonate intermediate shown as the product of equation (2). It has, of course, also been experimentally demonstrated that the product of equation (3) is in fact obtained.

An alternate method for synthesis of those compounds of this invention where R_1 is substituted by chlorine or bromine consists of the addition of halogen or hydrogen halide to the double bond of the com-

15 The dialkyl carbamoylphosphonates prepared as described above or by methods described in the chemical literature are readily hydrolyzed to the monoester salt compounds of this invention by addition to aqueous ammonia or amine solutions. This procedure may be used therefore to obtain a "mixed" product, comprising a salt of one amine and an amide of another. This will be discussed and exemplified below.

20 The dialkyl carboalkoxyphosphonates and dialkyl carbamoylphosphonates used for the synthesis of the compounds of this invention can be prepared by methods available in the literature, such as Nylen, Chem. Ber. 57, 1023 (1924) and Reetz et al., J.A.C.S. 77, 3813-16 (1955) using appropriate ester intermediates. Generally, the alkoxy group of the carboalkoxyphosphonate is limited for practical purposes to methyl and ethyl, since there appears to be no advantage to increasing the size of the alcohol moiety. However, higher alcohol derivatives are useful in some instances.

25 35 The following are illustrative of typical diesters of the carboalkoxyphosphonates:

Diethyl carbomethoxyphosphonate
Diallyl carbomethoxyphosphonate
Diisopropyl carboethoxyphosphonate
Dibutyl carbobutoxyphosphonate
Dimethylallyl carboethoxyphosphonate

40 The following are illustrative of typical carbamoylphosphonate esters:

45 Diethyl carbamoylphosphonate
Diallyl N,N-dimethylcarbamoylphosphonate
Diallyl carbamoylphosphonate
Dipropyl N-methylcarbamoylphosphonate
Dimethyl piperidinocarbonylphosphonate
Bis(2-chloroethyl)carbamoylphosphonate

The following are illustrative of the amines which can be used for the amination and/or hydrolysis of the esters:

50 Ammonia
Methylamine
Dimethylamine
Allylamine
Propylamine
Ethylamine
Morpholine
Piperidine
Methylhydrazine
N,N-Dimethylhydrazine
Ethanolamine

55 60 65 More particularly, in the preferred procedure for preparing the ammonium alkyl carbamoylphosphonates of this invention, a dialkyl carboalkoxyphosphonate or dialkyl carbamoylphosphonate is added to a stirred aqueous solution of ammonia or other amine.

Stirring is continued until a clear solution is obtained. The resultant salt can then be isolated by removal of the water through evaporation or by stripping under reduced pressure. In general, these salts are stable white crystalline solids or viscous liquids. Those which are solid can be recrystallized from one or a mixture of several lower alcohols. However, most of the products are suitable for use without purification.

It is preferred that an excess of ammonia or amine be employed in this reaction to insure good yields and rapid reaction. A ratio of diester to amine of 1 to 2 or greater is employed. Preferably the ratio of diester to amine of between 1 to 2 and 1 to 10 is employed. The excess amine insures that amidation of the carboxylic ester rather than hydrolysis is the predominant reaction.

It is also preferred that a concentration of ammonia or amine of from 25 to 50 percent be employed, although the reaction can be operated at higher or lower concentrations.

When the amine reactant is not highly soluble in water, another solvent, such as methanol or ethanol can be added to the aqueous system to solubilize the amine reactant and thereby increase its reactivity.

This process can conveniently be carried out at about room temperature, although higher temperatures can also be employed if it is desired to speed up the rate of reaction. This process is moderately exothermic, and therefore must be controlled by regulation of the diester addition rate and/or by external cooling to maintain the desired temperature.

A highly satisfactory procedure is to slowly add the diester to a stirring aqueous solution of the amine

and alkaline earth metals by interchanging the ammonium salt with appropriate bases or salts.

Another method is to convert the ammonium salt to the free acid, and then neutralize the free acid with the appropriate base or salt.

The following illustrative examples are presented to further illustrate this invention. In the following examples, parts and percentages are by weight unless otherwise specified.

10

EXAMPLE 1

A solution of 48.5 parts of 29 percent aqueous ammonium hydroxide is stirred and cooled with an external ice bath to 15°C. To the cooled solution 22 parts of 15 diallyl carbomethoxyphosphonate is slowly added over a 10-minute period. The mixture turns cloudy, but clears up after about 15 minutes. During this time, the mixture is allowed to warm spontaneously to about 30°C. and stirring is continued for 2 hours. The clear solution is stripped under reduced pressure (15 mm of Hg) at a water-bath temperature or 70°C. The residue is a white crystalline solid which is recrystallized from absolute ethyl alcohol, giving 12.3 parts of ammonium allyl carbamoylphosphonate, m.p. 160°–162.5°C. Non-aqueous titration either as an acid or a base gives a molecular weight of 182±1.

20

25

30

EXAMPLES 2–9

The procedure of Example 1 is repeated by substituting an equivalent amount of the indicated "Phosphonate Ester" for the diallyl carbomethoxyphosphonate of Example 1 to produce the indicated "Salt Product."

Ex.	Phosphonate Ester	Salt Product
2	diethyl carboxymethoxyphosphonate	ammonium ethyl carbamoylphosphonate m.p. 173–176
3	bis(2-chloroethyl)carbomethoxyphosphonate	ammonium 2-chloroethylcarbamoylphosphonate, m.p. 117–120
4	diethyl carboethoxyphosphonate	ammonium butyl carbamoylphosphonate m.p. 205.5–206.5
5	diallyl carboethoxyphosphonate	ammonium allyl carbamoylphosphonate
6	dimethylallyl carbomethoxyphosphonate	ammonium methylallyl carbamoylphosphonate, m.p. 193–197
7	diisopropyl carboethoxyphosphonate	ammonium isopropyl carbamoylphosphonate, m.p. 213–216 (dec.)
8	diethyl carbomethoxyphosphonate	ammonium methyl carbamoylphosphonate, m.p. 148–151
9	dipropyl carbopropoxyphosphonate	ammonium propyl carbamoylphosphonate, m.p. 190–192 (dec.)
10	diisobutyl carbomethoxyphosphonate	ammonium isobutyl carbamoylphosphonate, m.p. 221–222 (dec.)
11	dihexyl carbomethoxyphosphonate	ammonium hexyl carbamoylphosphonate, m.p. 212 (dec.)
12	bis(1-ethyl-2-butetyl)carbomethoxyphosphonate	ammonium (1-ethyl-2-butetyl)carbamoylphosphonate
13	bis(2-methoxyethyl)carbomethoxyphosphonate	ammonium 2-methoxyethyl carbamoylphosphonate
14	bis(2-bromopropyl)carbomethoxyphosphonate	ammonium 2-bromopropyl carbamoylphosphonate
15	bis(6-chlorohexyl)carbomethoxyphosphonate	ammonium 6-chlorohexyl carbamoylphosphonate
16	bis(6-bromohexyl)carbomethoxyphosphonate	ammonium 6-bromohexyl carbamoylphosphonate
17	bis(2-butoxyethyl)carbomethoxyphosphonate	ammonium 2-butoxyethyl carbamoylphosphonate, hygroscopic solid
18	bis(2,2,2-trichloroethyl)carbomethoxyphosphonate	ammonium 2,2,2-trichloroethylcarbamoylphosphonate
19	bis(2,2,2-tribromoethyl)carbomethoxyphosphonate	ammonium 2,2,2-tribromoethylcarbamoylphosphonate

which is cooled and maintained at about 15°C. When addition of the diester is complete, the temperature of the mixture is allowed to come to room temperature or slightly above. Generally, the reaction is complete in a few minutes to several hours depending on the reactants and conditions used.

The ammonium salts prepared as described above can be converted to salts of other bases or of alkaline

65

EXAMPLE 20

To a stirring ice-chilled solution of 35 parts 40 percent methylamine in water is added slowly 8.4 parts of dimethyl carbomethoxyphosphonate. The mixture is warmed to 25°C. and allowed to stir for 3 hours. The clear solution on stripping under reduced pressure yields 9.6 parts methylammonium methyl N-methylcar-

bamoylphosphonate as a colorless oil. The product analyzes for the dihydrate.

EXAMPLES 21-27

The procedure of Example 20 is repeated substituting an equivalent amount of the indicated "Aqueous Amine" for the methylamine of Example 20 and an equivalent amount of the indicated "Phosphonate Ester" for the dimethylcarbomethoxyphosphonate of Example 20 to obtain the indicated "Salt Product." Most of the indicated "Salt Products" are isolated as liquids or low melting solids.

Ex.	Aqueous Amine	Phosphonate Ester	Salt Product
21	methylamine (40%)	diethyl carboethoxyphosphonate	methylammonium ethyl N-methylcarbamoylphosphonate
22	methylamine (40%)	diisopropyl carbomethoxyphosphonate	methylammonium isopropyl N-methylcarbamoylphosphonate
23	methylamine (40%)	diallyl carboethoxyphosphonate	methylammonium allyl N-methylcarbamoylphosphonate
24	dimethylamine (25%)	diethylcarbomethoxyphosphonate	dimethylammonium ethyl N,N-dimethylcarbamoylphosphonate
25	methylhydrazine (50%)	diethyl carboethoxyphosphonate	methyl carbazoylphosphonic acid, monoethyl ester, salt with methylhydrazine
26	piperidine (50%)	dibenzyl carbomethoxyphosphonate	piperidinium benzyl piperidinocarbonylphosphonate
27	1,1-dimethylhydrazine (35%)	dipropyl carbomethoxyphosphonate	1,1-dimethylhydrazinium propyl 3,3-dimethylcarbazoylphosphonate

EXAMPLE 28

Eight parts of diethyl N-methylcarbamoylphosphonate is added slowly to 18 parts of a 29 percent aqueous solution of ammonia, while holding the temperature at 25°C. by external cooling. The unreacted ammonium hydroxide is allowed to evaporate, giving a white, crystalline, solid residue. Recrystallization from absolute ethanol gives 5 parts of ammonium ethyl N-methylcarbamoylphosphonate, m.p. 189°C.

EXAMPLES 29-41

The procedure of Example 28 is repeated substituting an equivalent amount of the indicated "Aqueous Amine" for the ammonia of Example 28 and an equivalent amount of the indicated "Phosphonate Ester" for the diethyl methylcarbamoylphosphonate of Example 28 to obtain the indicated "Salt Product."

Ex.	Aqueous Amine	Phosphonate Ester	Salt Products
29	ammonia (20%)	diphenyl N-methyl carbamoylphosphonate	ammonium phenyl N-methyl carbamoylphosphonate

-Continued

Ex.	Aqueous Amine	Phosphonate Ester	Salt Products
30	methylamine (25%)	dimethyl N,N-dimethyl carbamoylphosphonate	methylammonium methyl N,N-dimethylcarbamoylphosphonate
31	diethylamine (25%)	diethylcarbamoylphosphonate	dimethylammonium ethyl carbamoylphosphonate
10	allylamine (25%)	diallyl carbamoylphosphonate	allylammonium allyl carbamoylphosphonate
33	isobutylamine (20%)	diisopropyl N-methyl carbamoylphosphonate	isobutylammonium isopropyl N-methylcarbamoylphosphonate
15			
34	methylamine (20%)	diisopropyl morpholinocarbonylphosphonate	methylammonium isopropyl morpholinocarbonylphosphonate
20	triethanolamine	diallyl carbamoylphosphonate	triethanolammonium allyl carbamoylphosphonate
35			
36	ammonia (29%)	diethyl pyrrolidinocarbonylphosphonate	ammonium ethyl pyrrolidinocarbonylphosphonate, m.p. 189-192 (dec.)
25			
37	ammonia (29%)	diethyl morpholinocarbonylphosphonate	ammonium ethyl morpholinocarbonylphosphonate, m.p. 183-185 (dec.)
30			
38	ammonia (29%)	diethyl N,N-dimethylcarbamoylphosphonate	ammonium ethyl N,N-dimethylcarbamoylphosphonate, m.p. 140.5-142.5
35	39	ammonia (29%)	ammonium 3-butynyl N,N-dimethylcarbamoylphosphonate
40	ammonia (29%)	diethyl N-methylcarbamoylphosphonate	ammonium ethyl N-methylcarbamoylphosphonate
40	41	ammonia	ammonium ethyl aziridiniumcarbamoylphosphonate
45			

EXAMPLE 42

To a mixture of 12.1 parts of ammonium allylcarbamoylphosphonate and 100 parts of ethanol is added dropwise 8 parts of bromine. The reaction mixture is filtered giving 8.5 parts of ammonium 2,3-dibromopropyl carbamoylphosphonate, m.p. 175-177°C.

EXAMPLES 43-44

The procedure of Example 42 is repeated substituting an equivalent amount of the indicated "Alkenyl Reagent" for the ammonium allylcarbamoylphosphonate of Example 42 and an equivalent amount of the indicated "Halogen" for the bromine of Example 42 to obtain the indicated "Product."

43	ammonium methylallyl carbamoylphosphonate	chlorine	ammonium 2,3-dichloro-2-methylpropyl carbamoylphosphonate
65			
44	ammonium but-2-enyl carbamoylphosphonate	bromine	ammonium 2,3-dibrometyl carbamoylphosphonate

EXAMPLE 45

An aqueous solution of 45 parts ammonium hydroxide is stirred and chilled with an ice bath, while 24.4 parts benzyl methyl carbomethoxyphosphonate is added slowly. Stirring is continued until a clear solution is obtained. Unreacted ammonium hydroxide and water are removed from the mixture under reduced pressure, leaving as a solid residue ammonium mono-benzyl carbamoylphosphonate, m.p. 186, after recrystallization from ethanol.

EXAMPLES 46-51

The procedure of Example 45 is repeated substituting an equivalent amount of the indicated "Aqueous Amine" for the ammonium hydroxide of Example 45 and an equivalent amount of the indicated "Phosphonate Ester" for the benzyl methyl carbomethoxyphosphonate of Example 45 to obtain the indicated "Salt Product" as a principal product of this procedure.

Ex.	Aqueous Amine	Phosphonate Ester	Salt Product
46	methylamine (40%)	benzyl methyl carbomethoxyphosphonate	methylammonium benzyl N-methylcarbamoylphosphonate
47	ammonia (29%)	methyl phenyl carbomethoxyphosphonate	ammonium phenyl carbamoylphosphonate, m.p. 197-199 (dec.)
48	dimethylamine (25%)	butyl ether carbomethoxyphosphonate	dimethylammonium butyl N,N-dimethylcarbamoylphosphonate
49	ethylamine (50%)	methyl propargyl carbomethoxyphosphonate	ethylammonium propargyl N-ethylcarbamoylphosphonate
50	allylamine (25%)	methyl allyl carboethoxyphosphonate	allylammonium allyl N-allyl carbamoylphosphonate
51	pyrrolidine (30%)	methyl propyl carbomethoxyphosphonate	pyrrolidinium propyl pyrrolidinecarbamoylphosphonate

EXAMPLE 52

To a stirring suspension of 21.2 parts ammonium butyl N-methylcarbamoylphosphonate and 100 parts methanol is added 42 parts of a 40 percent solution of N-benzyltrimethylammonium hydroxide in methanol. Ammonia and methanol are stripped from the mixture at 40°C. under reduced pressure, leaving benzyltrimethylammonium butyl N-methylcarbamoylphosphonate as a residue.

EXAMPLES 53-56

The procedure of Example 52 is repeated substituting an equivalent amount of the indicated "Base" for the N-benzyltrimethylammonium hydroxide of Example 52 and an equivalent amount of the indicated "Ammonium Phosphonate" for the ammonium butyl N-methylcarbamoylphosphonate of Example 52 to obtain the indicated "Salt Product."

Ex.	Base	Ammonium Phosphonate	Salt Product
53	5 tetraethylammonium hydroxide	ammonium allyl carbamoylphosphonate	5 tetraethylammonium monoallyl carbamoylphosphonate
54	5 trimethylamine (large excess)	ammonium ethyl N-methylcarbamoylphosphonate	5 trimethylammonium monoethyl N-methylcarbamoylphosphonate
55	10 ethanolamine	ammonium methallyl hexahydroazepino-carbonylphosphonate	ethanolammonium methallyl hexahydroazepinocarbonylphosphonate
56	benzylamine	ethylammonium isopropyl carbamoylphosphonate	benzylammonium isopropyl carbamoylphosphonate

EXAMPLE 57

20 A 5 percent aqueous solution of ammonium ethyl carbamoylphosphonate is passed through a packed column of sulfonated polystyrene copolymer hydrogen-type resin to convert the salt to the free acid. Evaporation of the water gives a residue of the acid ester, ethyl carbamoylphosphonic acid, m.p. 130°C.

EXAMPLES 58-60

30 The procedure of Example 57 is repeated, first obtaining the indicated "Acid Ester" in aqueous solution and then removing the water to obtain the water-free product, usually a solid.

Ex.	Ammonium Phosphonate	Acid Ester
58	ammonium methyl N-methylcarbonylphosphonate	methyl N-methylcarbamoylphosphonic acid
59	ammonium isopropyl carbamoylphosphonate	isopropyl carbamoylphosphonic acid
40	ammonium alkyl carbamoylphosphonate	alkyl carbamoylphosphonic acid

EXAMPLE 61

45 A 5 percent aqueous solution of ammonium propyl N-methylcarbamoylphosphonate is passed through a packed column of sulfonated polystyrene copolymer hydrogen type resin to convert the salt to the free acid. This is neutralized with the equivalent amount of sodium bicarbonate to give a solution of essentially pure sodium propyl N-methylcarbamoylphosphonate. Evaporation of this solution gives the solid salt product.

EXAMPLES 62-75

55 The procedure of Example 61 is repeated, first obtaining the free acids of the indicated "Ammonium Phosphonate" as was done in Example 61 and then neutralizing the acid with the indicated "Base" according to the procedure of Example 61 to obtain the indicated "Salt Product."

Ex.	Ammonium Phosphonate	Base	Salt Product
62	ammonium phenyl carbamoylphosphonate	sodium bicarbonate	sodium phenyl carbamoylphosphonate

Ex.	Bicarbonate Salt	Carbamoyl-phosphonate	Salt Product
77	sodium bicarbonate	ammonium ethyl N-methylcarbamoyl-phosphonate	sodium ethyl N-methylcarbamoyl-phosphonate
78	potassium bicarbonate	ammonium benzyl carbamoylphosphonate	potassium benzyl carbamoylphosphonate
79	tetramethylammonium bicarbonate	ammonium monoallyl piperidinocarbonylphosphonate	tetramethylammonium allyl piperidino-carbonylphosphonate
80	benzyltrimethylammonium bicarbonate	ammonium butyl carbamoylphosphonate	benzyltrimethylammonium butyl carbamoylphosphonate

—Continued

Ex.	Ammonium Phosphonate	Base	Salt Product
63	ammonium benzyl carbamoylphosphonate	calcium hydroxide	hemicalcium benzyl carbamoylphosphonate
64	ammonium ethyl carbamoylphosphonate	barium hydroxide	hemibarium ethyl carbamoylphosphonate
65	ammonium methyl-N,N-dimethylcarbamoylphosphonate	hydroxyethyltrimethylammonium hydroxide	hydroxyethyltrimethylammonium methyl N,N-dimethylcarbamoylphosphonate
66	ammonium benzyl carbamoylphosphonate	benzyltrimethylammonium hydroxide	benzyltrimethylammonium benzyl carbamoylphosphonate
67	ammonium allyl carbamoylphosphonate	magnesium hydroxide	hemimagnesium allyl carbamoylphosphonate
68	ammonium butyl N-methyl carbamoylphosphonate	morpholine	morpholinium butyl N-methylcarbamoylphosphonate
69	ammonium trimethylamine	monoisopropyl morpholino-carbonylphosphonate	trimethylammonium isopropyl morpholine carbonylphosphonate
70	ammonium ethyl carbamoylphosphonate	tetrabutylammonium hydroxide	tetrabutylammonium ethyl carbamoylphosphonate, hygroscopic solid
71	ammonium ethyl carbamoylphosphonate	lithium carbonate	lithium ethyl carbamoylphosphonate, m.p. above 300°C.
72	ammonium ethyl carbamoylphosphonate	zinc carbonate	hemizinc ethyl carbamoylphosphonate, m.p. 244 (dec.)
73	ammonium isopropyl carbamoylphosphonate	dodecylamine	dodecylammonium isopropyl carbamoylphosphonate
74	ammonium allyl carbamoylphosphonate	manganous carbonate	hemimanganous allyl carbamoylphosphonate
75	ammonium butyl morpholiniumcarbonylphosphonate	dodecyltrimethylammonium hydroxide	dodecyltrimethylammonium butyl morpholiniumcarbonylphosphonate

EXAMPLE 76

To a stirred solution of 10 parts of potassium bicarbonate and 50 parts of water is added 18.4 parts ammonium isobutyl carbamoylphosphonate. Stirring is continued until solution is complete. The solution is evaporated to dryness, giving the solid product, potassium isobutylcarbamoylphosphonate.

EXAMPLES 77-80

The procedure of Example 76 is repeated substituting the indicated "Bicarbonate Salt" for the potassium bicarbonate of Example 76 and an equivalent amount of the indicated "Carbamoylphosphonate" for the ammonium monoisobutyl carbamoylphosphonate of Example 76 to obtain the indicated "Salt Product."

15 Formulation

Plant growth modifying compositions of the present invention can be prepared by admixing at least one of the compounds of this invention with pest control adjuvants or modifiers to provide compositions in the form of dusts, water-soluble powders, solutions, granules or pellets. In addition, the plant growth modifying agents such as maleic hydrazide and "Alar" (N-dimethylaminosuccinic acid) can be included in the compositions of this invention in combination with the compounds of this invention.

20 Compositions of the invention, may contain as a conditioning agent one or more surface-active agents, sometimes called surfactants, in amounts sufficient to render a given composition containing the compounds of this invention readily soluble in water or capable of wetting foliage efficiently.

The surface-active agent used in this invention can be a wetting, dispersing or an emulsifying agent which will assist dispersion and solution of the active compound.

25 35 The surface-active agent or surfactant can include such anionic, cationic and non-ionic agents as have heretofore been generally employed in plant control compositions of similar type. Suitable surface-active agents are set forth, for example in "Detergents and Emulsifiers" 40 1967 Annual by John W. McCutcheon, Inc.

In general, less than 10 percent by weight of the surface-active agent will be used in compositions of this invention and ordinarily the amount of surface-active agents will range from 1-5 percent but may even be less than 1 percent by weight.

45 Additional surface-active agents can be added to the formulations to increase the ratio of surfactant:active ingredient up to as high as 5:1 by weight. Such compositions may have a greater effectiveness than can be expected from a consideration of the activity of the components used separately. When used at higher rates, it is preferred that the surfactant be present in the range of one-fifth to five parts surfactant for each one part of active agent.

55 Water-Soluble Powders

Water-soluble powders are compositions containing the water-soluble active material, an inert solid extender which may or may not be water-soluble, and optionally one or more surfactants to provide rapid wetting and solution. A buffer, which may also function as an extender, can be present to improve formulation stability and to control the pH of the final spray solution.

65 The classes of extenders suitable for the water-soluble powder formulations of this invention are the natural clays, diatomaceous earth, synthetic mineral

fillers derived from silica and silicate, starch, sugar, and inorganic salts. Most preferred fillers for this invention are kaolinites, attapulgite clay, montmorillonite clays, synthetic silicas, synthetic magnesium silicate, calcium sulfate dihydrate, and disodium hydrogen phosphate.

Suitable surfactants for use in such compositions are those listed by J. W. McCutcheon in "Detergents and Emulsifiers" 1967 Annual. Among the more preferred surfactants are the non-ionic and anionic type, and those most suitable for the preparation of the dry, soluble products of this invention are solid forms of compounds known to the art as wetters and dispersants. Occasionally a liquid, non-ionic compound classified primarily as an emulsifier may serve as both wetter and dispersant.

Most preferred wetting agents are alkylbenzene- and alkylnaphthalene-sulfonates, sulfated fatty alcohols, amines or acid amides, long-chain acid esters of sodium isethionate, esters of sodium sulfosuccinate, sulfated or sulfonated fatty acid esters, petroleum sulfonates, sulfonated vegetable oils, and tertiary acetylenic glycols. Preferred dispersants are methylcellulose, polyvinyl alcohol, lignin sulfonates, polymeric alkylnaphthalene-sulfonates, sodium naphthalenesulfonate, polymethylene bisnaphthalenesulfonate, and sodium N-methyl-N-(long chain acid) taurates.

Wetting and dispersing agents in these preferred water-soluble compositions of this invention are usually present at concentrations of from about 0.5 weight percent to 5 weight percent. The inert extender then completes the formulation. Where needed, 0.1 weight percent to 1.0 weight percent of the extender may be replaced by a corrosion inhibitor or an anti-foaming agent or both.

Thus, water-soluble formulations of the invention will contain from about 25 to 95 weight percent active material, from 0.5 to 2.0 weight percent wetting agent, from 0.25 to 5.0 weight percent dispersant, and from 4.25 to 74.25 weight percent inert extender, as these terms are described above.

When the water-soluble powder contains a corrosion inhibitor or an anti-foaming agent or both, the corrosion inhibitor will not exceed about 1 percent of the composition, and the anti-foaming agent will not exceed about 0.5 percent by weight of the composition, both replacing equivalent amounts of the inert extender.

Solution Concentrates

The aqueous solution concentrates are prepared by mixing a water-soluble active compound of this invention with water. A portion of the water may be replaced with methanol, ethanol, isopropanol, ethylene glycol, cellosolve or methyl cellosolve. Surfactants and buffering agents can optionally be present.

These aqueous solution concentrates will contain from 15 to 60 percent of active ingredient, and from 40 to 85 percent water or mixture of water and hydroxylated organic solvent. Surfactants, corrosion inhibitors, buffering and anti-foam agents may also be included in which case they may replace up to 10 percent of the solvent system.

Dusts

Dusts are dense powder compositions which are intended for application in dry form, in accordance with

the preferred compositions and methods of the invention. Dusts are characterized by their free-flowing and rapid settling properties so that they are not readily windborne to areas where their presence is not desired.

5 They contain primarily an active material and a dense, free-flowing, solid extender.

Their performance is sometimes aided by the inclusion of a wetting agent, and convenience in manufacture frequently demands the inclusion of an inert, adsorptive grinding aid. For the dust compositions of this invention, the inert extender may be either of vegetable or mineral origin, the wetting agent is preferably anionic or non-ionic and suitable adsorptive grinding aids are of mineral origin.

15 Suitable classes of inert solid extenders for use in the dust compositions are those organic or inorganic powders which possess high bulk density and are very free-flowing. They are also characterized by possessing relatively low surface areas and are poor in liquid adsorption.

20 Suitable classes of grinding aids are natural clays, diatomaceous earths, and synthetic mineral fillers derived from silica or silicate. Among ionic and non-ionic wetting agents, the most suitable are the members of 25 the group known to the art as wetting agents and emulsifiers. Although solid agents are preferred because of ease in incorporation some liquid non-ionic agents are also suitable in the dust formulations.

Preferred inert solid extenders for the dusts of this 30 invention are micaceous talcs, pyrophyllite, dense kaolin clays, tobacco dust and ground calcium phosphate rock such as that known as "Phosphodust," a trademark of the American Agricultural Chemical Company.

35 Preferred grinding aids are attapulgite clay, diatomaceous silica, synthetic fine silica and synthetic calcium and magnesium silicates. Preferred wetting agents are those previously described under water-soluble powder formulations.

40 The inert solid extenders in the dusts of this invention are usually present in concentrations of from about 30 to 90 weight percent of the total composition. The grinding aid will usually constitute 5 to 50 weight percent of the composition, and the wetting agent will constitute from about 0 to 1.0 weight percent of the composition. Dust compositions can also contain other surfactants such as dispersing agents in concentrations of up to about 0.5 weight percent.

45 The water-soluble powders described above can also 50 be used in the preparation of dusts. While such water-soluble powders could be used directly in dust form, it is more advantageous to dilute them by blending with the dense dust diluent. In this manner, dispersing agents, corrosion inhibitors, and anti-foam agents may also be found as components of a dust.

55 Thus, the dust compositions of this invention will 60 comprise about 5 to 20 weight percent active material, 5 to 50 weight percent adsorptive filler, 0 to 1.0 weight percent wetting agent, and about 30 to 90 weight percent dense, free-flowing dust diluent, as these terms are used herein. Such dust formulations can contain, in addition, minor amounts of dispersants, corrosion inhibitors, and anti-foam agents, derived from the water-soluble powders used to make the dusts.

Granules and Pellets

65 Under some circumstances it may be advantageous

to apply the compounds of this invention in the form of granules or pellets. Suitable carriers are natural clays, some pyrophyllites and vermiculites. Wetting agents of the type listed by J. W. McCutcheon in "Detergents and Emulsifiers" 1967 Annual can also be present to aid leaching of the active component.

One method of preparation suitable for both granules and pellets involves blending the active ingredient with clays, water-soluble salts, surfactants and a small amount of water. After pelleting and/or granulating, the formulation is dried prior to use. A second method suitable for the preparation of granules formulation involves spraying a solution of the active material on porous, adsorptive, preformed clay or vermiculite granules. Surfactants listed by McCutcheon can also be included in the spray solution. After drying, the granules are ready for application.

The preferred granules or pellets will contain about 5 to 30 weight percent of active material, about 0 to 5 weight percent wetting agent and about 65 to 95 weight percent inert mineral carrier.

Paints and Dressings

Although the formulations described above can be used to apply the compounds of formula (1) to cut portions of plants, it is often preferable to incorporate them in conventional tree wound dressings which are commonly used in the trade. Thus, in one step, the cut can be protected and regrowth in the pruned area can be inhibited.

Having high water solubility, the compounds can readily be incorporated in the aqueous phase of conventional asphalt emulsion dressings and water based paints. At the low levels employed (1 - 5 percent), there is generally little effect on the physical properties of the systems, and commercial materials need not be reformulated. At relatively high levels, the active ingredient, being a salt can cause conventional emulsions to thicken or break. In the former case mere dilution with water is effective to restore physical properties; in the latter case, a salt-tolerant emulsifier must be selected.

As the compounds of formula (1) have rather low solubility in organic solvents, they must be finely ground and well dispersed to be effective in systems such as solvent-based varnishes and paints. In such systems, the active ingredient must be treated as a pigment would be. Additionally, water must be rigorously excluded, otherwise the active material will not remain well-dispersed.

When packaged as an aerosol, similar considerations apply. The preferred type of formulation is an emulsion with the compound of formula (1) in the aqueous phase and the film former, solvent and propellant system in the organic phase. Dispersions in organic systems are possible but not preferred because of difficulty in assuring adequate mixing before use, the need to rigorously exclude moisture, and the expense of assuring an adequately fine particle size.

Application

As stated earlier, this invention is founded on the discovery that the compounds of formula (1) are useful for modifying the growth rate of plants. More particularly the compounds of this invention are useful as plant growth retardants. They also affect the flowering and fruit set of numerous plants.

The term plant growth retardant as used in this disclosure is to be understood to mean an agent which when applied to a plant or its environs will slow the growth of the plant without killing or causing extensive injury to said plant. This also includes a delaying response on bud sprouting or prolonging of the dormancy period.

The compounds of this invention can be used to retard bud break and the growth of woody vegetation.

10 The compounds of this invention can also be used to control the growth of turf and other herbaceous vegetation.

15 The compounds of this invention can be applied as foliar sprays or as soil applications to retard the growth rate of such plants or to affect flowering and fruit set.

Preferably, the compounds of this invention are applied as a foliar spray to the point of runoff although lower-volume application may also be effective.

20 It is preferred that the application be made a short time prior to the period when maximum plant growth is anticipated, but application can also be made during the dormant stage or just after the plants have been trimmed. Or if flowering and fruit set are to be modified, the treatment is applied before, during, or shortly after flowering.

25 To prevent bud break it is preferred that the application be made at the time the buds for the next year are being developed. For most plants this is from July to a few weeks before leaf-fall.

30 It will be recognized that the rate of application is dependent upon the species to be treated and the results desired. In general, rates of from 0.25 to 20 kilograms per hectare are used although higher or lower rates can achieve the desired effect in some instances.

35 The following examples are presented to further illustrate the formulation and application of the compounds of this invention. Parts and percentages in the following examples are by weight unless otherwise indicated.

EXAMPLE 81

40 A dust having the following formula is prepared.

Ammonium allyl carbamoylphosphonate	5.0%
Talc	64.0%
Attapulgite	30.0%
Sodium benzenesulfonate	1.0%

45 The active component is ground with the minor diluent and the surfactant to pass a 0.149 mm. screen. This material is then blended with the major diluent to form a dust composition.

50 It will be understood that the other compounds of this invention can also be formulated in a like manner.

55 The dust formulation of Example 81 is applied, using a helicopter, at a rate of 100 kilograms per hectare to an area under an electric power line in which the brush and trees have been freshly trimmed in spring at the time when the leaves on most of the plants are just fully expanded. The application is made in the early morning when the foliage is wet with dew or just after a rain. 60 This treatment retards the growth of a large number of species along the right-of-way including the following species: red maple (*Acer rubrum*), black willow (*Salix*

nigra), hawthorn (*Crataegus spp.*), sweet gum (*Liquidambar styraciflua*) and yellow poplar (*Liriodendron tulipifera*).

EXAMPLE 82

A water-soluble powder of the following formula is prepared.

Ammonium allyl carbamoylphosphonate	95.0%
Synthetic silica	3.5%
Disodium hydrogen phosphate	1.0%
Diethylsodium sulfosuccinate	0.5%

The above ingredients are mixed and then ground to pass a 0.42 mm. screen. The resulting formulation is water-soluble powder, with the exception of the synthetic silica conditioning agent.

The following compounds of this invention can also be formulated in like manner.

Ammonium 2-chloroethyl carbamoylphosphonate
Ammonium methyl carbamoylphosphonate
Sodium phenyl carbamoylphosphonate
Hemicalcium benzyl carbamoylphosphonate
Hemibarium ethyl carbamoylphosphonate
Ammonium 2,3-dibromopropyl carbamoylphosphonate
Diethylammonium ethyl carbamoylphosphonate
Ammonium hexyl carbamoylphosphonate

Four kilograms of the water-soluble powder formulation of Example 82 is dissolved in 200 liters of water and 0.5 percent of a non-phytotoxic wetting agent is added. This solution is sprayed on one hectare of freshly trimmed Norway maple (*Acer plantanoides*) growing along struts under a power line. This treatment greatly reduces the rate of growth of the trees and extends the time interval between trimmings. The trees are not significantly injured by the treatment.

The water-soluble powder of Example 82 can be dissolved in water at the rate of 2,000 p.p.m. of active ingredient and applied to 1 acre of Virginia bunch peanuts at the time they are beginning to flower. The treatment prevents excessive vegetative growth and promotes flowering and fruit set of the treated plants. As a result of the treatment the plants are easier to harvest and dry and more high quality nuts are harvested.

Example 83

Ammonium ethyl carbamoylphosphonate	90%
Silica aerogel	4%
Sugar	6%

The ingredients are combined, blended, crushed through a U.S.S. No. 20 sieve (0.84 mm. openings) and rebalanced.

In mid-September, active ingredient formulated as described above was dissolved in water containing 0.2 percent sorbitan monolaurate and applied to the foliage of red maple (*Acer rubrum*), sweet gum (*Liquidambar styraciflua*) and green briar (*Smilax spp.*) at the rate of 3 kg/ha in 800 l. of water. The treatment had no apparent effect on the plants for the remainder of the season. However, the next July the treated plants had developed almost no leaves. What buds that had broken had produced only minute red-tinged leaves. Except for some tips, the bare branches were still alive. The floor beneath the treated brush was green with herbaceous vegetation.

EXAMPLE 84

A wettable powder of the following formula is prepared.

5	Hemibarium benzyl carbamoylphosphonate	50.0%
10	Montmorillonite	43.0%
	Synthetic silica	4.0%
	Disodium hydrogen phosphate	1.0%
	Sodium alkylnaphthalenesulfonate	1.0%
	Sodium lignin sulfonate	1.0%

The above ingredients are mixed and then ground to pass a 0.25 mm. screen. The active ingredient in the above formulation dissolves when the composition is added to water.

Twenty kilograms of the formulation of Example 84 is added to 400 liters of water and agitated until the active ingredient dissolves. This solution is then sprayed on 1 hectare of newly trimmed hedgerow in the spring after the leaves have expanded. This treatment greatly reduces the growth of plants growing in the hedgerow such as osage orange (*Maclura pomifera*), but does not seriously injure them. The hedgerow is thus kept neat with a minimum of labor expended for trimming it.

EXAMPLE 85

A solution of the following formula is prepared.

30	Ammonium ethyl carbamoylphosphonate	24.0%
35	Disodium hydrogen phosphate	1.0%
	Sodium laurylsulfate	0.5%
	Water	74.5%

The above components are blended to form a homogeneous solution.

The following compounds can be formulated in like manner.

40	Benzyltrimethylammonium benzyl N,N-dimethylcarbamoylphosphonate
45	Trimethylammonium ethyl N-methylcarbamoylphosphonate
	Methylammonium isopropyl morpholinocarbonylphosphonate

Triethylammonium ethyl carbamoylphosphonate
Ten kilograms of the solution prepared in Example 50 are added to 200 liters of water and applied with a fixed boom sprayer to one hectare of Kentucky bluegrass (*Poa pratensis*) turf growing along a highway in early June. This treatment greatly reduces the rate of growth of the bluegrass for a period of 4 to 8 weeks and the mowing required to maintain the area in an attractive condition is reduced.

EXAMPLE 86

A solution of the following formula is prepared.

60	Allyl ammonium allyl N,N-dimethylcarbamoylphosphonate	24.0%
65	Trimethylpolyethyleneglycol ether	1.0%
	Water	20.0%
	Ethylene Glycol	55.0%

The above components are blended to form a homogeneous solution.

The following components can be formulated in like manner.

Ethanolammonium methylallyl hexahydroazepino-carbonylphosphonate

Dodecyltrimethylammonium butyl N-methylcarbamoylphosphonate

Ammonium n-hexyl carbamoylphosphonate

Six kilograms of the formulation of Example 86 are added to 400 liters of water containing 0.5 percent Tween 20 (polyoxyethylenesorbitan monolaurate). This solution is sprayed to runoff on a freshly trimmed privet (*Ligustrum ovalifolium*) in May. The treatment greatly reduces the growth of the hedge. Little labor is required to keep it attractive all season.

A solution containing 227 gms. of active ingredient formulated as above is sprayed on an area of red delicious apple trees about 2 weeks after petal fall. This treatment prevents the "June drop" and gives a higher yield of apples per acre than that from a similar untreated acre of trees. It also reduces the growth of spurious sheets known as "water sprouts" and ameliorates the tendency to biannual bearing which is strong in this variety.

EXAMPLE 87

The following formulation is prepared.

Ammonium methyl carbamoylphosphonate	25.0%
Sodium lauryl sulfate	50.0%
Magnesium silicate	10.0%
Kaolinite	15.0%

The above components are blended, micropulverized to pass a 0.30 mm. screen and reblended.

The following compounds can be formulated in like manner.

Morpholinium ethyl carbamoylphosphonate

Sodium phenyl carbamoylphosphonate

Hemicalcium benzyl carbamoylphosphonate

Five kilograms of the formulation of Example 87 are suspended in 100 liters of water and then sprayed to runoff on freshly trimmed trees and brush along the edge of a power line right-of-way. This treatment greatly reduces the growth of the trees and shrubs without permanent injury to them and they are prevented from growing over into the power line. The vegetation on the right-of-way is controlled by applying herbicides. This treatment reduces the labor required to maintain the line.

EXAMPLE 88

An aqueous concentrate solution is prepared which contains the following ingredients:

ammonium ethyl carbamoylphosphonate	24.0%
N-dimethylaminosuccinic acid	12.0%
water	32.0%
methanol	32.0%

The above ingredients are stirred together with slight warming until a homogeneous solution results.

A water solution of the formulation of Example 88 is prepared to contain 600 p.p.m. total active ingredient. This solution is sprayed on McIntosh apples to run-off

in early September. The treatment prevents coloration in the apples and prevents premature fall before the apples are harvested.

Example 89

Ammonium ethyl carbamoylphosphonate	41.5%
Water	58.5%

The ingredients are combined and stirred to produce a solution containing approximately 4 pounds active ingredient per gallon (480 g. per liter). After filtration through a bed of diatomaceous earth, the product is packed in glass or plastic containers until use.

In September, oaks (*Quercus spp.*), hickory (*Carva spp.*) and Loblolly pine (*Pinus taeda*) were treated with a foliar spray of the above formulation at the rate of 6 kg/ha in 800 liters of water. The treated plants showed no response that fall but next spring the deciduous species failed to develop new leaves and the pine did not develop new shoots. The treatment had prevented the new buds from breaking in the spring although plant stems and limbs were observed to be alive when examined closely.

EXAMPLE 90

The following wettable powder is prepared:

ammonium ethyl carbamoylphosphonate	30.0%
maleic hydrazide	20.0%
synthetic silica	2.5%
montmorillonite	45.0%
sodium alkylnaphthalene sulfonate	2.0%
partially desulfonated sodium lignin sulfonate	0.5%

The above ingredients are blended, micropulverized to a particle size essentially below 50 microns and reblended.

The wettable powder of Example 90 is suspended in water at the rate of 4,000 p.p.m. of active ingredient and sprayed on an area of mixed brush under a power line. The application is made in mid-May just after the brush has been trimmed back to keep it away from under the power line. The solution is sprayed to run-off on the lower two-thirds of the trees which were not cut. This treatment effectively retards the growth of the trimmed vegetation for the next growing season as well as the one in which the vegetation is treated.

The formulation of Example 90 is suspended in water at the rate of 1,000 p.p.m. of active ingredient and sprayed to the point of run-off on single trees located at random throughout orchards of apple, peach and cherry varieties. The treatments are applied while the trees are still in the dormant stage. During an early spring warm period the trees in these orchards begin to break dormancy and buds sprout. The treated trees, on the other hand, remain dormant and do not sprout nor flower while there is danger of frost. In this manner, a more reliable yield is assured.

EXAMPLE 91

The following aerosol preparation is prepared:

(ammonium ethyl carbamoylphosphonate	1.0%
(water	29.0%
(asphalt	20.0%
(xylene	25.0%
